UNITED STATES PATENT OFFICE.

JOHN H. GOODFELLOW, OF BUFFALO, NEW YORK.

BOILER-TUBE SUCKER AND SOOT EJECTOR.

Application filed October 7, 1919, Serial No. 329,041. Renewed July 25, 1923.

To all whom it may concern:

Be it known that I, JOHN H. GOODFELLOW, a citizen of the United States, and resident of Buffalo, in the county of Erie and State 5 of New York, have invented certain new and useful Improvements in Boiler-Tube Suckers and Soot Ejectors, of which the following is a specification.

This invention relates to boiler flue 10 suckers and soot ejectors, particularly that kind adapted for causing a suction within the flue while forcibly ejecting the dirt and soot from one end thereof.

One of the objects of my invention is to 15 provide a flue cleaner having a re-direct nozzle for forcibly emitting jets of compressed air or steam within the tube to be cleaned, in a direction contrary to the flow of the cleaning fluid to the said nozzle.

20 A further object of my invention is to provide a method of cleaning flues, whereby there is created a vacuous condition at one end of the tube to suck in air, and a forcibly ejected flow of air with the cleaning fluid 25 from the opposite end of the flue.

Another object of this invention is to provide an elbow extension to the end of the flue to be cleaned, at the ejection end, whereby the ejected soot and ashes may be 30 carried by a tubular connection to a stack, as it is ejected.

A further object is to provide in such an elbow a self-sealing connection where the same is attached to the flue.

35 Another object is to provide with such a self-sealing elbow a renewal part at the outer portion of the elbow where the same receives the abrasion from the ejected material passing through it, so that such an elbow may be repaired by renewing such 40 wearable part.

A further object is to provide with such an elbow tubular connections for passing the cleaning fluid therethrough to a re-direct 45 nozzle positioned within the flue.

With these and other objects in view, one embodiment of my invention is illustrated in the drawings, its construction is described, its operation is explained, and what I claim 50 is set forth.

In the drawings,

Figure 1 illustrates a form of my invention applied to a boiler tube, and is partly shown in section.

55 Figure 2 is a longitudinal sectional view of the valve, the handle being omitted.

Figure 3 is a front view of the nozzle.

Figure 4 is a plan view of the rear wall repair plate of said nozzle showing the inside thereof.

60 Figure 5 is a top plan of the re-direct nozzle.

Figure 6 is an end view of the re-direct nozzle.

In the figures, the improved form of elbow 65 1, is provided with a cylindrical flange 2, within which is fitted a ring 3, having an external flange 4. The flange 4 has an annular recess 5, formed to fit over the beaded end of a boiler flue 6. There is 70 provided an annular extension 7, adapted to fit within the cylindrical end of the boiler flue 6. Extending into the flue 6, integral with the annular extension 7, are the fingers 8, which are in contact with the inner wall 75 of the flue 6 and assist in supporting the elbow in engagement therewith. Upstanding from the lower of the fingers 8, is the dividing fin 8^a. A tubular boss 9 projects within the ring 3 and is in threaded engagement 80 with the pipes 10 and 11, forming a continuous passage with said pipes. The opposite end of the pipe 11 is in threaded engagement with the body of the re-direct nozzle 12, having a curved cavity 13, with 85 an outlet 14, directed parallel to the axis of the pipe 11. The body of the re-direct nozzle 12, has an extension 15, in which is fixed the pivotal bolt 16, having journaled thereon the roller 17, in contact with the 90 wall of the flue 6.

Considering the elbow 1, the same has a renewable curved wall 18, upon which is provided a tongue 19, fitting within a lip 20, the upper end of the wall 18 being held 95 in place by the bolt 21. There are provided side lips 22, to the wall 18, which engage and lap over the outside of the body of the elbow 1. The pipe 10 passes through a hollow boss 23, on the wall 18 and extends beyond the same into threaded engagement with a socket 24, there being provided a washer 25 between the boss 23 and the socket 24. Directly below and in contact with the pipe 10, is a cleaving projection 26 to the wall 18, 100 which serves to divide the fluid currents passing through the elbow on each side of the pipe 10. The elbow 1 is secured at the bottom of its lower end to the ring 3 by means of the bolt 27.

110 I sometimes make the elbow 1 in small sizes for small flues, having the elbow cast

in one place, and thereby avoid the complication of construction shown in Figure 1, by not having the wall 18 renewable, yet making the outer curved wall extra thick 5 to take the wear from the grit which is thrown against this wall.

If desired, a plurality of such devices as herein shown and described, may be provided whereby several flues can be cleaned at 10 the same time.

Considering now the supply conduits connected with the pipe 10, there is shown an angular connection 28, in threaded engagement with a short piece of pipe 29, which in 15 turn is threaded into the socket 24. The angular connection 28 has a tubular branch 30, to which is attached a supply pipe 31, having a quickly operable valve 32. A handle 33, fitting into the branch 34, is provided for easy manipulation of the device. 20

In operation, assume that the device is in place as shown in Figure 1, engaging the flue 6, with the nozzle 12 positioned between the ends thereof, and that the outer end of 25 the elbow 1 has tubular connection with a chimney or other place where the soot and dirt about to come from the flue is discharged. Assume also that the pipe 31 is connected with a source of steam or other 30 cleaning fluid supply under pressure. The valve 32 is then opened and the cleaning fluid proceeds through the tubular connections to the nozzle 12 and is forcibly ejected at the outlet 14 and directed back to the 35 elbow 1, through the ring 3. Upon striking the fin 8^a, the current of cleaning fluid laden with soot and dirt, is divided and this division is further maintained by the projection 26 where its course is bent by the 40 curved wall 18 of the elbow 1. The divided portions of the current pass on either side of the pipe 10 and out of the elbow 1 into the connections, which continue to carry the currents to the place for depositing the removed soot and dirt. The currents produced 45 between the nozzle 12 and the elbow 1, induce a suctional current from the opposite end of the flue 6, toward the nozzle 12, upon reaching which, they are divided by the pointed formation of the end 50 of the nozzle 12 and continue on. These currents, suctionally induced, are picked up by the forceful current, flowing from the opening 14 of the nozzle 12 and mingle with the remainder of the forced currents. 55

It is evident that the blast of currents thus formed against the curved wall 18, of the elbow 1, laden as they are with abrasive soot, rust and dirt, will wear upon this wall 60 18, and for that reason I make the same renewable and of a harder material than the body of the elbow. And for the same reason I make the connections, which must be separable on account of the necessity of renewing this part, easily separable. If the 65

operator desires to use the device as a direct blowing apparatus he can easily convert the same by removing the re-direct nozzle 12 and blowing through the end of the pipe 10, to which a direct nozzle can be attached if 70 desired.

Inasmuch as changes in the details of construction of the one embodiment of my invention here shown and described can be made without departing from the spirit and 75 scope of the invention, I do not wish to be confined to the one embodiment. Hence I claim:

1. In mechanism for cleaning a flue, the combination of an elbow, a ring carried by 80 said elbow and having an external flange adapted to engage the end of said flue, a supply pipe carried by said elbow and ring, and a re-direct nozzle at the inner end of 85 said pipe.

2. In mechanism for cleaning a flue the combination of an elbow, a ring carried by 90 said elbow and having an external flange adapted to engage the end of said flue, a supply pipe carried by said elbow and ring, and means on said nozzle arranged to bear against the inner wall of said flue and support the inner end of said supply pipe. 95

3. In mechanism for cleaning a flue, the combination of an elbow, a ring carried by 100 said elbow and having an external flange adapted to engage the end of said flue, a fin upstanding in said ring, a supply pipe carried by said elbow and ring, and a nozzle at the inner end of said pipe. 105

4. In mechanism for cleaning a flue, the combination of an elbow, a ring carried by 110 said elbow and having an external flange adapted to engage the end of said flue, and an annular extension adapted to fit within the end of said flue, a fin upstanding within 115 said annular extension, a supply pipe carried by said elbow and ring, and a nozzle at the inner end of said pipe.

5. In mechanism for cleaning a flue, the combination of a ring having an annular extension, a dividing fin in said extension, a supply pipe through said ring, a re-direct nozzle on said pipe within said flue and an extension from said nozzle in line with said 120 fin. 115

6. In mechanism for cleaning a flue, the combination of an elbow, a ring carried by 125 said elbow and having an external flange and an annular extension, a dividing fin in said extension, a supply pipe through said ring, a re-direct nozzle on said pipe within said flue, an extension from said nozzle and a cleaving projection on said elbow, said nozzle extension, dividing fin and cleaving 125 projection cooperating to divide the currents set up in said flue.

7. A flue cleaner comprising a supporting elbow, a removable section forming the outer curve of said elbow, a ring fixed to 130

said elbow having a formation adapted to fit within a flue to be cleaned and forming a supporting connection with said flue, a supply conduit passing through said elbow,

5 a nozzle device adapted to be positioned within said flue having connection with said conduit, regulating means on said conduit for regulating the supply of cleaning fluid passing through said conduit and said nozzle, and tubular means for directing the discharge of the cleaning fluid at an angle away from said flue.

8. In mechanism for cleaning a boiler tube, a nozzle having parallel inlet and outlets 15 ports at the same end, and a cleaving edge at the opposite end to divide the current of soot set up by the action of said nozzle.

9. In mechanism for cleaning a boiler tube, a pipe adjacent one side of the tube, a redirect nozzle carried by said pipe, said nozzle having an outlet at the center of the tube, and a cleaving edge at its inner end, a cleaving extension from said nozzle and a 25 roller on said extension for supporting said nozzle.

10. In mechanism for cleaning a boiler tube, an elbow adapted to be mounted on the end of the tube, for guiding the ejected 30 material away from the operator, a plate in said elbow and a pipe supported by said plate, said plate having a thickened portion below said pipe to cleave the flow of ejected material and prevent its direct contact with 35 said pipe.

11. In mechanism for cleaning a boiler tube, a pipe, a redirect nozzle supplied by said pipe, and having a single outlet and means removably fixed at the end of said 40 tube for supporting said pipe adjacent the side of the tube and said nozzle at the center of the tube.

12. In mechanism for cleaning a boiler tube, a pipe located adjacent the side of the 45 tube, a redirect nozzle supplied by said pipe,

having a single outlet at the center of the tube, a roller on the underside of said nozzle, and means removably fixed at the end of said tube, said means and roller coacting to support said pipe and nozzle in operative 50 position.

13. Mechanism for cleaning boiler tubes comprising an elbow adapted to be fixed on one end of the tube to be cleaned and a nozzle carried by said elbow and adapted to 55 project into said tube when said elbow is in position.

14. Mechanism for cleaning boiler tubes comprising an elbow, a ring removably fixed in one end of said elbow and having a flange 60 to engage the mouth of the tube to be cleaned, a line of pipe carried by said elbow and said ring, a nozzle at the end of said pipe, a roller on said nozzle, a supply pipe carried by said elbow, a quickly operable 65 valve in said supply pipe and a handle, said elements forming a unitary structure, the pipe and nozzle of which is introduced into the tube to be cleaned until the flange on said ring engages the mouth of said tube. 70

15. Mechanism for cleaning boiler tubes, comprising an elbow, a flange ring removably mounted at one end of said elbow, a section of pipe carried by said ring and said elbow, a second section of pipe carried by 75 said ring in line with said first section, a nozzle on said second section, a roller carried by said nozzle to support said nozzle and the inner end of said second section by pipe, a supply pipe carried by said elbow 80 in line with said first section, a quickly operable valve in said supply pipe and a handle on said supply pipe.

Signed at Buffalo, in the county of Erie and State of New York, this 24th day of 85 September, A. D. 1919.

JOHN H. GOODFELLOW.
